UNITED STATES PATENT OFFICE.

HARRY L. WOOD, OF DOWAGIAC, MICHIGAN, ASSIGNOR TO PREMIER WARM AIR HEATER COMPANY, OF DOWAGIAC, MICHIGAN, A CORPORATION OF MICHIGAN.

WATER-PAN FOR HOT-AIR FURNACES.

1,379,325.

Specification of Letters Patent. Patented May 24, 1921.

Application filed June 25, 1920. Serial No. 391,763.

To all whom it may concern:

Be it known that I, HARRY L. Wood, a citizen of the United States of America, residing at Dowagiac, in the county of Cass and State of Michigan, have invented certain new and useful Improvements in Water-Pans for Hot-Air Furnaces, of which the following is a specification, reference being had therein to the accompanying drawings.

This invention relates to water pans for hot air furnaces and it is the object of the invention to provide a water pan having an improved swinging closure which may be conveniently manipulated and which will return into the water pan any water that may be spilled thereupon while the pan is being filled.

Still another object is to provide a closure for the water pan of a furnace, which closure when in open position will retain any condensation that may have accumulated thereupon instead of draining the same upon the floor.

A preferred embodiment of the invention is illustrated in the accompanying drawing, wherein:

Figure 1 is a view in front elevation of a fragmentary portion of a furnace equipped with the herein described improved water pan;

Fig. 2 is a vertical sectional view of the same taken upon the line 2—2 of Fig. 1.

In these views the reference character A designates a furnace wall and B a water pan formed integral with or secured to said wall, said water pan having a portion projecting exteriorly of the wall A as is common practice. This projecting portion of the water pan B is provided with a closure

C which is hinged at the front thereof to the forward edge of the water pan as indicated at D and which is provided at a suitable point with a lug E forming a handle by which said closure may be raised or lowered. 45 The open position assumed by said closure is illustrated in dash lines in Fig. 2. The free edge of the closure C, that is to say the edge adjoining the wall A when the closure is seated, is provided with a depending 50 flange F which is adapted to seat upon a ledge G integrally formed upon the portion of the wall A above said water pan. The flange F is continued around the entire periphery of the closure C so that said closure 55 in its open position forms a shallow vessel which is adapted to catch such water as may be spilled thereupon while the pan B is being filled and which furthermore will serve to retain any condensation which may have 60 accumulated upon the under surface of the closure while the same is seated. Thus such water as may have been spilled upon said closure or accumulated thereon due to condensation is not permitted to drain off upon 65 the floor but is retained and returned into the pan B when the closure is again seated.

What I claim as my invention is:

In a device of the character described, the combination with the wall of a hot air furnace, of a water pan projecting exteriorly therefrom, a closure for said projecting portion hinged at its outer edge to the outer edge of said exteriorly projecting portion and provided with a flange around its entire inner edge, and means adjacent the wall of said furnace forming a seat for the closure. 75

In testimony whereof I affix my signature.

HARRY L. WOOD.
